UNITED STATES PATENT OFFICE.

OLOF OHLSON, OF WEST NEWTON, MASSACHUSETTS, ASSIGNOR TO WALTHAM WATCH COMPANY, OF WALTHAM, MASSACHUSETTS, A CORPORATION OF MASSACHUSETTS.

CONTROL FOR THE SETTING AND WINDING STEM OF WATCHES.

1,145,699.

Specification of Letters Patent.

Patented July 6, 1915.

Application filed October 23, 1914. Serial No. 868,219.

To all whom it may concern:

Be it known that I, OLOF OHLSON, a citizen of the United States, residing at West Newton, in the county of Middlesex and 5 State of Massachusetts, have invented certain new and useful Improvements in Control for the Setting and Winding Stems of Watches, of which the following is a specification.

10 The present invention relates to watches and other time pieces of the type in which the main spring is wound and the hands are set, when necessary, by manipulation of the same stem or crown, which projects at the 15 circumference of the watch case.

In stem-wound and -set watches heretofore produced, it has been common to use the same stem and crown for both winding and setting, by making the stem movable end- 20 wise and arranging it to be operative for setting when pulled out, and to be operative for winding when pushed in, or the reverse, and the apparatus in which my present invention is embodied is of this type.

25 The present invention involves improvements in the control means for the stem of a stem-wound and-set time piece which provides a positive lock for preventing movement of the stem into its setting position by 30 any force, however great, applied directly to the stem crown, but enables the stem to be automatically placed in the setting position when such lock is released; and which also enables the whole mechanism and control to 35 be located inside of the inner periphery of that part of the watch case which is called the case center.

The improvements above referred to secure certain advantages which will be duly 40 set forth in the following specification, following a detailed description of the herein illustrated embodiment of the invention.

In the accompanying drawings,—Figure 1 is an elevation of a control device in which 45 my present invention is embodied, in connection with the winding and setting stem of a time piece, and the plates of the movement which are located adjacent thereto, the case center and stem crown of the time piece being shown in section. Fig. 2 is a fragmentary view similar to Fig. 1, showing the setting stem in setting position (such stem being shown in Fig. 1 in winding position),

and also showing the clutches and gears connected with the setting stem, in section.

55

Referring to the drawings,—*a* represents the ring-shaped member of a watch case which surrounds the periphery of the movement, and to which the covers of the case are connected, this member being commonly 60 called the case center.

b represents generally the frame of a watch movement contained in the case, and *c* represents the winding stem which extends to a greater or less extent through the case 65 center, and which carries the setting and winding crown *d* on its outer end, outside of the case center. In general, the construction of the stem *c* is or may be like the stems heretofore used for the purpose, and in these 70 drawings I have illustrated one well known form of stem and associated parts, but with the addition of a new feature to the stem. Such stem has a square, or otherwise non-circular portion *e* fitting a similarly formed 75 socket *f* in a sleeve *g* which turns in suitably arranged bearings in the movement frame. The stem bears against a push pin *h* passing through the bore of the sleeve *g* and terminating in a head *i* outside of the inner end 80 of the sleeve. Said sleeve has a bearing surface *j*, on which is rotatably mounted a spur pinion *k*, which may be called the winding pinion, having a face clutch on its inner side. The remainder of the sleeve is provided with 85 a non-circular surface *l*, preferably square, on which is mounted a complementary clutch member *m* having a bore which fits the surface *l* and is adapted to slide thereon. This clutch member coacts with the clutch-teeth 90 of the pinion *k* and is provided with a groove *n* receiving the end of an arm *o*, and on its lower end it has crown gear teeth *p* for meshing with the setting train of the watch movement.

95

The arm *o* or clutch shifter referred to is formed as a part of a lever which is pivoted to the frame on a fulcrum stud *q* and has a short arm *r* provided with bearing surfaces *s* and *t* and with a shoulder *u*. A floating dog *v* has a foot portion *v'* which underlies and presses against the push pin *h*; a cam surface *v*² which bears against an abutment *w*, mounted on the movement frame, and an end *v*³ which engages the 105 short lever arm *r* on either of the surfaces *s*.

or t . A spring α is engaged with the shoulder u of the lever r and is also engaged with the floating dog v at a shoulder v^4 thereof. The spring α is in the form of a bow and is under such tension that when placed as shown, with its ends engaging the shoulders u and v^4 , it applies force tending to move the points or shoulders u and v^4 toward each other.

- 10 The setting stem is provided with a collar 1, having a square locking face 2, on one side, and an inclined cam face 3 on its opposite side. Coacting with this collar is a latch 4, which is formed as a rocking piece pivoted on a stud 5, secured to the movement frame, and having a resilient finger portion 6 which bears against an abutment 7 of the movement frame at the opposite side of the pivot 5 from the toe of 15 the latch, under such tension that it presses the latch toward the collar 1. This latch has a tail portion 8, extending along the inner surface of the case center, in position to be pressed upon by a sliding stud 9, which 20 passes through the case center and may be depressed by pressure applied by the fingernail of the user, or any other instrument, in a well known manner.

15 The normal position of the parts is that shown in Fig. 1, where the stem is in its innermost position and is there held by the latch 4 which overlies the collar 1, the spring finger 6 holding the latch in this position, which is the locking position. The 25 push pin h is at this time pushed inwardly, placing the dog v where its surface adjacent to the end of the inclined surface v^2 bears on the abutment stud w , and causing its end v^3 to bear on the incline t of the lever r , 30 swinging this lever so that the arm o is raised and the sliding clutch member m is coupled with the spur pinion k , and the crown gear element p on this clutch member is brought out of mesh with the setting train. This arrangement of the parts causes 35 rotation of the crown to turn the winding pinion k through the engagement of the clutch member m with the winding wheel, it being understood that such clutch member 40 is compelled to rotate with the crown on account of the non-circular portion e of the stem, the correspondingly formed socket of the sleeve g , and the non-circular exterior l of said sleeve which fits the correspondingly 45 formed bore of the clutch member m . In this position of the parts, the spring α is in 50 its most expanded position, that is, its ends are more widely separated than when in any other position, and it is therefore under 55 increased stress. If, now, it is desired to set the hands of the watch, the user presses upon the stud 9 which, by its engagement with the tail piece 8 of the latch, swings the latter out of engagement with the collar 1, and releases the stem. The

latter is now moved outwardly into the position shown in Fig. 2, through the action of the spring α , which moves the floating dog v bodily to the left (with respect to the drawings) and causes the foot v' of said dog to be raised through the action of the cam surface v^2 on the abutment w , and to move the push pin h outwardly, thereby correspondingly moving the stem. This movement of the dog causes its tail v^3 to press on the surface s of the lever r , and to swing the arm o of such lever downwardly, moving the clutch member out of connection with the winding pinion k and causing the crown gear element p to engage the setting train. This described movement of the lever r is brought about by the spring α , because the point at which it presses on the lever r through the tail v^3 of the dog is further removed from the axis of the lever 75 than is the reacting point of the spring on said lever, which point is at the shoulder u , both these points being, however, on the same side of the pivot. This movement occurs instantly, upon the withdrawal of the 80 latch 4 from the collar 1. The parts are now in such a condition that the rotation of the crown will set the hands of the time piece and will not wind the main spring, because the winding wheel is now disengaged 85 from the clutch element m , and the sleeve g is free to rotate within said wheel. The pressure applied to the stud 9 to accomplish this result may be relieved immediately, 90 whereupon the latch springs into engagement with the inclined inner surface 3 of the collar 1, with no other effect than to assist in retaining the stem in its projected position. After setting the hands, all that 95 need be done to return the parts to the winding position, is to press inwardly on the crown d . The latch 4 presents no hindrance to inward movement of the stem, because the inclined surface 3 pushes it out of the way against the yielding resistance of the spring 100 finger 6, and when the collar has passed the latch, the latter automatically slips over into engagement with the surface 2, which is perpendicular to the axis of the stem. Inward movement of the stem, of course, restores 105 the parts to the position shown in Fig. 1, through the action of the push pin h and the reaction of the abutment stud w on the dog v , and the action of the latter on the lever r , which moves the clutch member m outwardly, as already described. 110

115 Among the advantageous results secured by the mechanism above described, may be named the following:

First, the stem is located in the winding 120 position positively, whereby it becomes possible to use the stem as a means for suspending the watch.

Second, the entire mechanism controlling the stem is located within the periphery of 125

the case center, whereby it is possible to place the crown close to the case center, and it becomes unnecessary to provide what is commonly known as a pendant, that is, a sleeve projecting from the case center, which has heretofore been commonly employed for retaining the controlling devices of stem-wound and-set watches.

Third, the push stud 9 may be released immediately after being used, and need not be continually pressed down during the setting operation, nor need it be again operated to permit the stem to be restored to the normal position. In watches heretofore produced wherein the setting is controlled by a stud, such as stud 9, it has been uniformly necessary, so far as I am aware, to hold the stud in the displaced position until the hands have been set.

Fourth, it is unnecessary to pull out the crown, in order to place the mechanism in setting position, for the crown is automatically projected and the parts brought into the setting condition as soon as the controlling stud 9 is operated.

It is possible to make the surface 2 of the collar or abutment 1 on an incline to the stem, instead of square thereto, and in such case the stem may be pulled out into the setting position by force applied directly to the crown, the latch being displaced by the wedging action of the surface 2. While this modified arrangement sacrifices the feature of the positive lock to retain the stem in winding position, it does not sacrifice the other advantage of enabling the entire control means for the stem to be located within the case center, for the same latch or detent can be used and arranged as here shown, either as a positive or a yielding detent, when it is desired to produce a watch having the crown close to the case center and without a pendant.

It is also within the contemplation of my invention to employ a latch or detent such as that here shown, and having the characteristic features herein described and claimed in a watch where the shifting of the stem between winding and setting positions is the reverse of that described and shown, by arranging the locking part of the latch on the inner side of the stem shoulder.

While this invention is applicable mainly to watches, I desire to say that I do not restrict its use to pocket watches, or to any particular class of time pieces, but that I have intended the term "watch" wherever used in the foregoing specification and in the following claims, to be considered as embracing any sort of time piece having a member in the nature of a stem or crown which is operable in connection with suitable mechanism for performing both functions of winding and of setting the hands of the time piece.

I claim:—

1. A time piece including in its construction a member adapted to be used for both winding and setting, and adapted to occupy different positions for performing its respective functions, means normally tending to place said member in one of its positions, and means located within the periphery of the movement frame arranged to prevent such movement and adapted to be displaced when desired to permit such movement. 70

2. A time piece including a case and a stem movable inwardly and outwardly with respect to said case and adapted for use to wind the watch and to set the hands, a lock 80 within the periphery of the movement frame positively preventing outward movement of said stem, and means for releasing said lock.

3. In a time piece, a winding and setting stem movable from one position to another, 85 in one of which it is operable for setting and in the other of which it is operable for winding, a displaceable lock supported on the movement frame normally retaining said stem in the winding position, and resilient 90 means tending constantly to move the stem from the winding into the setting position.

4. In a time piece, a winding and setting stem movable from one position to another, 95 in one of which it is operable for setting, and in the other of which it is operable for winding, yielding actuating means tending to place said stem in the setting position, a shoulder or abutment on the stem having a surface approximately perpendicular to the 100 direction in which the stem moves from one position to the other and at the side thereof toward which the stem moves into the setting position, a latch normally overlying said surface and being constantly 105 pressed toward the stem, said latch having a tail piece extending back from the stem adjacent to the wall of the case, and a stud passing through said wall movably and arranged to bear on said tail piece. 110

5. In a time piece, a case, a winding and setting stem passing through the case and being displaceable endwise from a position for winding to a position for setting, and back, a shoulder on said stem within the 115 case, and a latch movably mounted on the movement frame normally overlapping said shoulder when the stem is in one position, at the side of the shoulder toward which the stem moves when displaced into the other 120 position.

6. In a time piece, a case, a winding and setting stem passing through the case and being displaceable endwise from a position for winding to a position for setting, and back, a shoulder on said stem within the 125 case, a latch movably mounted on the movement frame normally overlapping said shoulder when the stem is in one position, at the side of the shoulder toward which the 130

stem moves when displaced into the other position, said latch and shoulder being so abrupt with respect to the line of movement of the stem as to make a positive lock against such movement, and means other than the shoulder for disengaging the latch from the shoulder.

7. In a time piece, a case, a winding and setting stem passing through the case and being displaceable endwise from a position for winding to a position for setting, and back, a shoulder on said stem within the case, a latch movably mounted on the movement frame and normally extending between the case and shoulder when the stem is in its inner position.

8. In a time piece, a displaceable winding and setting stem, an abutment on said stem, a latch arranged to overlap said abutment to prevent displacement of the stem, and having a spring finger held under such stress as to press the latch toward the stem, and means for displacing the latch from the stem.

9. In a time piece, a displaceable winding and setting stem, an abutment on said stem, a latch arranged to overlap said abutment to prevent displacement of the stem, said latch being pivoted to the frame of the watch with a locking portion adapted to overlap the said abutment when the stem is in one position, and having a spring finger pressing against an abutment of the frame and so reacting as to press said locking portion toward the stem.

10. In a time piece, a displaceable winding and setting stem, an abutment on said stem, a latch arranged to overlap said abut-

ment to prevent displacement of the stem, said latch being pivoted to the frame of the watch with a locking portion adapted to overlap the said abutment when the stem is in one position, and having a spring finger pressing against an abutment of the frame and so reacting as to press said locking portion toward the stem, the latch having also a tail piece, and means arranged to be pressed against such tail piece to displace the latch from the stem.

11. In a watch the combination with a movement frame and an annular case center surrounding said frame, of a winding and setting stem passing and movable endwise through the case center and having a shoulder, a latch pivoted to the movement frame provided with a locking part arranged to overlie said shoulder, with a tail piece extending along the inner wall of the case center, and with a resilient integral finger, the movement frame having an abutment against which said finger bears under stress tending to press said locking part over the shoulder, and a stud bearing on said tail piece and passing through the case center, the stud and locking part being on opposite sides of a line passing through the pivot point of the latch, whereby pressure applied through the stud to said tail piece causes withdrawal of the locking part of the shoulder against the tension of the resilient finger.

In testimony whereof I have affixed my signature, in presence of two witnesses.

OLOF OHLSON.
